UNITED STATES PATENT OFFICE.

LYLE REITH, OF MARION, INDIANA.

PENCIL ATTACHMENT.

1,200,238.

Specification of Letters Patent.

Patented Oct. 3, 1916.

Application filed November 20, 1915. Serial No. 62,565.

To all whom it may concern:

Be it known that I, LYLE REITH, a citizen of the United States, residing at Marion, in the county of Grant and State of Indiana, 5 have invented certain new and useful Improvements in Pencil Attachments, of which the following is a specification, reference being had to the accompanying drawings.

This invention relates to certain improvements in pencil attachments and has relation more particularly to a device of this general character especially designed and adapted for use by artists or the like; and it is an object of the invention to provide a 15 novel and improved attachment provided with means whereby thumb tacks or the like may be readily removed from applied position and wherein said means also serves as an ink retainer.

20 Furthermore, it is an object of the invention to provide an attachment of this general character provided with means whereby the pencil or the like to which it is applied is held against rolling movement and wherein 25 in said means serves as a linear measure.

The invention consists in the details of construction and in the combination and arrangement of the several parts of my improved pencil attachment whereby certain 30 important advantages are attained and the device is rendered simpler, less expensive and otherwise more convenient and advantageous for use, all as will be hereinafter more fully set forth.

35 The novel features of the invention will be carefully defined in the appended claim.

In order that my invention may be the better understood, I will now proceed to describe the same with reference to the accompanying drawings, wherein—

Figure 1 is a longitudinal sectional view taken through an attachment constructed in accordance with an embodiment of my invention, the same being shown in applied 45 position upon a writing implement; Fig. 2 is a bottom plan view of the device as herein disclosed; Fig. 3 is a side elevational view of my invention as herein disclosed; Fig. 4 is a transverse sectional view taken through 50 my improved attachment, with the writing implement removed; and Fig. 5 is a fragmentary elevational view illustrating the manner in which my improved attachment may be employed for extracting a thumb 55 tack.

As disclosed in the accompanying drawings, P denotes a pencil or other writing implement and A indicates my improved attachment as a whole.

As herein embodied, my improved attachment comprises the sleeve or ferrule 1 adapted to receive an end of the pencil P either to protect the point thereof or to lengthen the same so that the pencil may be employed with convenience and facility 60 when the pencil proper has been materially reduced in length.

It is to be noted that one end of the ferrule or sleeve 1 is provided with an open slot 2 so that the same may have the requisite 70 frictional engagement with the pencil. The opposite end of the ferrule or sleeve 1 is provided with a truncated closure member 3 which serves as a nib with which a pen point is adapted to coact, the inner end of the nib 75 being partially embraced by the clip 4 to retain the pen point a in applied position. Disposed longitudinally of the sleeve or ferrule 1 substantially the entire length thereof is the strip 5 substantially V-shape in cross 80 section which serves to prevent the pencil P from rolling and which also serves as a linear measure, one of the faces of said strip 5 being provided with inch graduations divided into sixteenths while the second face 85 is provided with inch graduations divided into tenths.

The forward end of the attachment A has secured to a side of the strip 5 the forwardly extending plate 6 having its forward or free extremity angularly disposed, as at 7, with its forward edge sharpened. The plate 6 and its angular end portion 7 serve as an extractor for a thumb tack, it being observed that the angular portion 7 95 permits the requisite leverage. It is also to be noted that when the pen point a is in applied position the plate 6 with the angular portion 7 serve as an ink retainer.

In view of what has been before described, 100 it is thought to be self-evident that a short drawing pencil may be made long enough by slipping the attachment on an end thereof. It will also be self-evident that the attachment may be readily applied over the 105 pointed end of the pencil to protect the same. It is to be noted that the sleeve or ferrule 1 adjacent its forward end is provided with an annular depression 8 affording an inwardly disposed rib which serves to limit 110

the extent of insertion of a pencil or other writing implement within the sleeve or ferrule.

From the foregoing description, it is thought to be obvious that a pencil attachment constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

23 I claim:

An attachment for a writing implement

consisting of an elongated sleeve having one end closed, said closed end portion being substantially truncated, a clip partially surrounding the sleeve and secured thereto at a point inwardly of the truncated end of the sleeve, said clip partially overlying the inner portion of said truncated end, and an elongated flat member secured to the sleeve at a point substantially diametric to the clip and extending in advance of the closed end of the sleeve, the outer end portion of the flat member being angularly disposed and intersecting the longitudinal plane occupied by the sleeve.

35 In testimony whereof I hereunto affix my signature in the presence of two witnesses.

LYLE REITH.

Witnesses:

ALBERT G. AILMAN,

RAYMOND F. HANCOCK.
